UNITED STATES PATENT OFFICE.

EDWARD L. LOWE, OF PALO ALTO, CALIFORNIA.

METHOD OF BURNING FUEL OIL IN INTERNAL-COMBUSTION ENGINES.

Application filed January 4, 1923. Serial No. 610,562.

To all whom it may concern:

Be it known that I, EDWARD L. LOWE, a citizen of the United States, residing in Palo Alto, in the county of Santa Clara, State of California, have invented a new and useful Method of Burning Fuel Oil in Internal-Combustion Engines, of which the following is a specification.

My invention, in its broad aspects, is a division of a contemporaneously pending application filed by me February 20, 1922, Serial No. 537,997, and relates to a novel method of burning fuel in the burner of an internal combustion engine whereby I am enabled to utilize with equal efficiency not only the cheapest and heaviest grades of hydro-carbons or oil, whose cost approximates from one to three cents per gallon, but also the lighter or more expensive hydro-carbons, such as gasoline or the like.

(1) At the present time ordinary internal combustion engine fuel oil has generally a flash point between 150° F. and 200°, and a fire test in the neighborhood of 250° or 300° F.

(2) Air when compressed to 200 pounds per square inch gauge is raised in temperature to about 670° F. Lower as well as higher compressive pressures have corresponding temperatures. It will be noted that the temperature of 670° is far in excess of that actually required to burn ordinary fuel oil, so that it will be seen that if now this temperature can in some way be utilized to ignite oil of combustion, as by the steps of my novel method, a new era in the operation of an internal combustion engine will be inaugurated.

My novel method of burning fuel is capable of being carried out in various forms of burners which I have invented, one form of which is shown in my pending application, Serial No. 537,997, aforesaid, while other embodiments are disclosed herein and my invention in its broad aspect consists in the utilization of the heat interchanges between the air of compression and the burner elements so as to segregate the lighter and heavier particles of the fuel, and the commingling of pure, compressed heated air admitted from an annular or exterior ignition chamber through restricted ports to said lighter fuel particles, which have been segregated by heat from the heavier particles and are contained in the upper portion of a central combustion chamber, from

which latter the ignited gases are permitted to travel or expand towards and into the compression space of the engine.

To the above ends my invention, in its broad aspects consists of the novel method, comprising admitting air to an engine cylinder and into the burner combustion and ignition chambers, next compressing said air within said combustion and ignition chambers and permitting a portion of the heat of said compressed air to be absorbed by the walls of said chambers, next expanding said air, next compressing said air and imparting additional heat to said burner elements to such an extent that ignition occurs on the admission of the fuel and the commingling of the upper lighter particles thereof with pure compressed air, admitted from said ignition chamber thereinto.

It further consists in admitting liquid fuel to a heated combustion chamber and segregating the lighter and heavier particles thereof so that said lighter particles are in the upper portion of said combustion chamber and next commingling said lighter particles in the upper portion of said combustion chamber with pure, compressed, heated, air admitted thereto thereby igniting the fuel.

It further consists in conjunction with the hereinabove described method, of the utilization of a thickened cap in metallic contact with the burner elements assembled in such a way that said cap is not so susceptible to quick changes of temperature, as are the burner elements, so that said cap automatically acts as a temperature regulating member, which is advantageous during the combustion stroke, as it provides means to keep the burner elements below destructive temperatures, whereby the latter function without overheating under all conditions of load or revolution, which indicates that the heat balance is reached which fulfills all requirements.

It further consists of a novel method of burning fuel, which consists in introducing fuel into a body of heated, compressed air to effect the segregation of the lighter and heavier particles thereof, initially igniting said lighter particles, next, admitting pure, compressed heated air into said lighter particles, and permitting the flame thus formed to expand into a zone of compressed air.

It further consists of a novel method of

burning fuel, which consists in introducing fuel into a confined body of heated compressed air and effecting the segregation of the lighter and heavier particles thereof, 5 primarily igniting said lighter particles by initially admitting pure, compressed heated air into said lighter particles, and lastly permitting the flame thus formed to expand into a zone of compressed heated air, where- 10 by a relatively gradual, slow, burning of the fuel occurs without an explosion.

For the purpose of illustrating my invention, I have shown different forms of apparatus wherein my novel process can be carried out, which are at present preferred by me, since they will give in practice satisfactory and reliable results; although it is to be understood that the various instrumentalities whereby my novel method can 20 be carried out can be variously arranged or organized within the scope of my invention and that my invention is not limited to the precise arrangement and organization of these instrumentalities as herein shown and 25 described.

Figures 1 and 7 represent vertical sectional views of different forms of apparatus wherein my novel method can be carried out.

30 Figures 2 and 3 represent, in detached position, perspective views of the burner seen in Figure 1.

Figure 4 represents, on an enlarged scale, a vertical, sectional view of the valve seen 35 in Figure 1.

Figure 5 represents on an enlarged scale a perspective view of the apertured head, stem and spring seen in Figure 1.

Figure 6 represents, on an enlarged scale, 40 the preferred manner of making a joint between the flange of the outer burner element and the cylinder.

Figures 8 and 9 represent perspective 45 views of the burner elements forming a complete burner seen in Figure 7.

Figure 10 represents a section on line 10—10 Figure 7.

Similar numerals of reference indicate 50 corresponding parts.

Referring to the drawings,

1 designates the engine cylinder and its water jacketed cylinder head and 2 the piston therein, which has its upper wall 3 preferably rounded or convex, the juxtaposed 55 wall 4 of the piston chamber 5 being preferably of the same contour as said piston end 3. The cylinder has the passage 6 in its upper portion and the air inlet 7 leading to the chamber 8, communicating with said 60 passage, which is controlled by the air intake valve 9. The exhaust chamber communicating with the passage 6 is indicated at 10, and is controlled by the exhaust valve 11, the exhaust escaping through the pipe 12.

65 My novel engine has no spark plugs, and

the valves 9 and 11 and the piston 3 are actuated by any suitable or conventional mechanism, which it is unnecessary to describe in detail.

13 designates a passage or pocket in the 70 top of the cylinder in which is positioned the burner 14 composed of a plurality of metallic ferrules, thimbles or sleeve-like members, which with their adjuncts constitute the salient features of my invention 75 and will now be described; said burner extending towards the compression space and having its end opening thereto.

The burner is composed of the outer member 15, which comprises a flange 16, having 80 the circumferential bottom shoulder 17, see Figure 6, which rests on the upper wall or edge of the pocket 13, the outer edge of said flange being beveled as at 48, (see Figure 6) and resting upon the gasket 18, which also contacts with the bevelled wall 49 of the flange 29, to be hereinafter referred to. From the flange 16 depends the hollow, open ended, conical thimble, ferrule or sleeve-like member 19 having the shape of a truncated 85 cone, whose diameter in cross section gradually increases downwardly and is preferably largest at its lower end 20.

21 designates an inner circumferential shoulder within the flange 16, upon which 90 rests the outer peripheral portion of the flange 22, from which depends the inner conical thimble, ferrule or sleeve-like member 23, which is of the shape of a truncated cone, whose diameter gradually increases 100 downwardly, the bottom edge 24 of the member 23, preferably terminating a short distance above the bottom 20 of the outer sleeves 19 and 23, and the inner central flaring combustion chamber 27, is contained with the 105 inner conical sleeve 23.

It will be seen from the foregoing that the conical sleeves 19 and 23, whose individual construction will be understood from Figures 2 and 3, when assembled as seen in 110 Figure 1, form a unit or burner 14 comprising the central flaring combustion chamber 27 of relatively large area flaring downwardly and the outer conical thin or restricted ignition chamber 26, which also 115 flares downwardly and discharges into the lower end of the outer sleeve 19, it being also apparent that the lower portion of the passage or pocket 13, in which the burner is positioned, also flares downwardly to meet 120 the wall 4, as indicated at 28. The burner or unit 14 is clamped in position by means of the base flange 29 of the valve casing 30, said flange being secured to the cylinder by bolts or the like 31, and by reason of the 125 gasket 18 being positioned as seen in Figure 6, the requisite tight joint between the various elements can be obtained by the employment of a single gasket.

32 designates the fuel inlet pipe for the 130

- admission of liquid fuel, which is secured to the extension 33 by the coupling 34, said extension projecting from the bonnet 35, which is secured within the valve casing 5 30 by the coupling nut 36, whose upper inner portion bears on the bonnet flange 37. The upward extension 33 of the bonnet 35 has the upper port 38, which admits the fuel upon the top of the valve 39, having 10 the ports 46, said valve having the pendant hollow guide 40, having the internal upper shoulder 41, see Figure 4. The upper end of the spring 42 bears against said shoulder 41 and its lower end bears on the head 43, 15 whose bottom is conical and rests on a conical seat above the flange 29, said head having the ports 44 therethrough, which communicate with the port 47 which admits the fuel directly into the combustion chamber 27. From the head 43 projects the stem 45 which is surrounded by the spring 42, the tendency of said spring normally being to seat the valve 39 upwardly, as seen in 20 Figure 1.
- 25 It will be seen from the foregoing that not only the burner and its adjuncts can be readily assembled and disconnected for the purpose of inspection, replacement or repairs, but the fuel control valve and its 30 adjuncts are also readily accessible, by the manipulation of the coupling nut 36.
- While I have shown in figures 1, 2 and 3, the preferred manner of constructing and assembling the burner elements 19 and 23, 35 with respect to the base flange 29, it will be evident that these elements may be differently constructed and assembled. It is, however, preferable that the burner elements 19 and 23 be of relatively thin metal 40 and that they be attached to or at least in metallic contact with the cap or base flange 29 which is of heavier metal or relatively thick, so that it is not so susceptible to quick changes of temperature, as are the thimbles 45 or burner elements 19 and 23, as will be hereinafter explained.
- The operation is as follows in a two cycle engine.
- In order to start, it is only necessary to 50 set the engine in motion or turn it over either by hand or by any one of the conventional methods now in use, and in the following description the term "inward" refers to the motion of the piston 55 towards the crank shaft, and "outward" the motion away from the crank shaft. The piston being at its inward position, the cylinder has received a charge of air at or near the atmospheric pressure.
- 55 The first outward stroke compresses the air with consequent increase in its temperature. This air fills all the compression space, entering all the spaces in and around the burner elements 19 and 23. The following heat 60 interchanges take place. The air in the
- space 13 relinquishes a portion of its heat to the jacket water through the cylinder head wall 4, and a portion to the thimble or outer burner element 19, and also a portion to the cap or flange 29. In like manner 70 the air in the space or ignition chamber 26 relinquishes heat to the thimbles or burner elements 19 and 23, and to the thick base flange or cap 29. The air in the combustion chamber or space 27 relinquishes heat to the thimble or inner burner element 23 and also to the cap or flange 29 which latter also receives the heat from said burner elements 19 and 23, by reason of its direct contact therewith.
- 75 As the piston moves inward after the first compressive stroke, the compressed air expands losing its heat and the air in the spaces 13, 26 and 27, while cooling obviously receives heat from the thimbles or burner elements 19 and 23 and from the cap or flange 29, which elements being made of metal lose their heat less rapidly than the air. When the piston reaches the end of 80 its inward stroke and a fresh charge of air enters and it moves outward again on its second compressive stroke, the burner and air within it are still warm, so that the interchange of heat between the burner and the compressed air will be less than on the first stroke, but interchanges of heat 85 take place in a similar manner. On the third stroke, the interchange will be less than on the second, and so on until the burner reaches a temperature approaching 90 that of the air of compression. When this point has been reached, a charge of fuel is allowed to enter the burner through the port or aperture 47. The oil first appearing 95 at the mouth of the opening 47 initially receives the heat during its passage through and contact with the cap or flange 29 and from air in the space or central combustion chamber 27. The heat given up by the air is immediately made up in part by radiation from the inner burner element or 100 thimble 23, and cap 29, and is sufficient to 105 burn the oil and ignite the charge, which is supplied by a piston pump to the inlet 32 and its discharge into the burner continues 110 over a fixed period of the cycle. The oil, therefore reaching the burner after the initial flash, burns upon its arrival within the burner and burns completely leaving no residue or carbon deposit. In fact, no oil 115 reaches the combustion space of the cylinder except in an incandescent state.
- 120 It will be readily appreciated that the ignition and burning of the charge materially alters the heat interchanges that take 125 place subsequent to ignition. The thin burner elements 19 and 23 are heated to a temperature in excess of that corresponding to the compressive pressure, and, in consequence upon each successive compressive 130

stroke, instead of receiving heat from the air of compression, they give up heat to it, or in other words, they are cooled by the air of compression. My novel burner 5 therefore functions to maintain a reasonably even temperature, the design thereof being such as to lend itself to this desired end.

It will be noted that the base flange or cap 29 is of heavier metal than the thin burner elements 19 and 23, which are in contact with it. The cap element 29 is therefore not so susceptible to quick changes of temperature as are the thimbles or burner elements 19 and 23, and thus acts as a temperature regulating member. During the combustion stroke, this is of special importance as it is the only means provided as illustrated to keep the thimbles or burner elements below destructive temperatures. The fact that my novel burner functions without overheating under all conditions of load or revolution indicates that the heat balance is reached which fulfills all requirements. From the foregoing it will now be apparent that should it be desired to use a compression pressure lower than that required to ignite low grade fuel oil by compression when the engine is cold, a lighter fuel oil with higher flash and fire test may be used for starting, and after the burner has received heat from combustion, the light oil may be shut off and the lower grade oil turned on to the burner. It will then continue to function on the low grade oil receiving and dispensing heat as described above.

It will be understood from the foregoing that the thin conical ignition chamber 26 and the central conical relatively large combustion chamber 27 are always filled with air during the period of compression. At or near the end of the compression stroke, fuel is slowly admitted through the passage 47 into the heated air due to compression contained in said combustion chamber 27. Due to the natural action of liquid fuel when subjected to heat inter-changes causing a partial "cracking" or separation of the lighter and heavier gases, the lighter gases naturally rise to the top of the combustion chamber 27, and the heavier gases remain suspended below the lighter gases in said combustion chamber which now contains a fuel which has slowly been admitted, and due to heat interchanges has become gasified to a greater or lesser degree, and is now commingled with the air in the combustion chamber heated by compression, which has caused the heat inter-changes between the thimbles and cap, as above explained.

As stated, the lighter gases are now at the top of the combustion chamber due to natural causes. Also due to the fact that

the lighter gases will ignite at a much lower temperature than the heavier gases, the series of ports 25, at the top of the combustion chamber 27 connecting with the outer thin ignition chamber 26, allow the lighter gases when they begin to ignite initially to come into contact with the pure compressed heated air in said ignition chamber and said pure highly heated air in the ignition chamber accelerates the burning of said lighter gases, which causes a very quick interchange of heat upon the thimble or burner element 23 surrounding the combustion chamber 27. There is no explosion in my novel device at any stage of the cycle, but instead a relatively slow progressive burning due to the fact that the oil is slowly admitted, the initial burning taking place in proximity to the ports 25, and a portion of the initial flame is in the upper part of both the ignition chamber and the combustion chamber. The burning of the gases progresses gradually downwardly and reaches the mouth of the burner communicating with the compression or working space of the cylinder, and the burning gases come in direct contact with the heated air in the compression space which causes a complete combustion of the gases above the piston, which in turn effects the actuation of the latter. The manner of exhausting the cylinder does not require special mention, the exhaust taking place through the passages 6, 10 and 12, and being controlled by the valve 11 operated by any conventional means. Especial attention is called to the co-action of the thickened cap 29, with the burner elements since its primary function is to absorb heat from the thin thimbles or burner elements during the combustion stroke, and thus reduce the temperature below the burning point.

The valvular mechanism seen in Figure 1, can be dispensed with if desired, and the fuel fed directly to the port 47, under which conditions the burner and its adjuncts will function perfectly.

I prefer under certain conditions and with certain grades of fuel to employ the valvular arrangement shown, wherein it will be apparent that the valve 39 will be unseated downwardly whenever the pressure in the pipe 32 is sufficient to overcome the tension of the spring 42, in which case the fuel will flow through the ports 46 and 44 to the passage 47 which I have shown as terminating in a nozzle in proximity to the ports 25, which nozzle may be omitted if desired.

It will be apparent that any back pressure in the burner or combustion chamber 27 will tend to seat the valve 39 upwardly, this upward seating tendency being augmented by the spring 43, as is evident.

While I preferably proportion the

lengths of the burner elements substantially as seen in Figure 1, and have shown them as being conical or flaring my device will function satisfactorily if concentric cylinders are employed, and if said burner elements are of substantially the same length.

I have found from an extensive practical use of my novel burner under all conditions and with varying grades of fuel that a greater efficiency is attained by the employment of the thin conical or flaring burner elements 19 and 23 whose lengths are proportioned substantially as shown, and I also in conjunction therewith employ the flaring mouth 28, which flaring constructions cause or enable the flame or expansive effect of the burnt gases somewhat to diverge and impinge substantially instantaneously upon the entire juxtaposed end area 3 of the piston, so that substantially every portion thereof receives the effect of the burnt gases. For this reason, one standard size of my novel burner composed of the flaring or conical burner elements 19 and 23 can be utilized as the burner unit for engines or pistons of a relatively wide range of sizes or diameters, as is evident.

Obviously, a plurality of burners 14 may be employed to a single cylinder, and when a plurality of said burners are employed, it will be evident that they may be disposed around or in the cylinder head in any desired arrangement which will produce the greatest efficiency. Additional thimbles may also be employed if desired.

While I preferably make the inner thimble somewhat shorter than the outer thimble, it will be apparent that the lengths of these thimbles may be proportioned differently from the construction shown, it being essential, however, that the central combustion chamber and the outer ignition chamber communicate at their upper and lower portions, the upper communication being had by the restricted ports 25.

In the construction seen in Figures 7 to 10, I have shown another form of apparatus, wherein my novel method can be carried out with equal efficiency and wherein the burner elements instead of being flaring or in the shape of truncated cones are composed of a plurality of cylinders or thin cylindrical thimbles assembled concentrically in the same manner as already described.

The outer cylinder or thimble 51 is provided with the flange 52 which is preferably supported on the engine cylinder in the manner already described with respect to Figure 1.

The head 52 is provided with the counter-bore 53 in which is seated the flange 54 which carries the thimble or cylinder 55 of the inner burner member, which is provided at its upper portion with the restricted ports 56.

The cylinders and their flanges composing the burner are held in assembled position in the same manner already described in Figure 1, by means of a thickened cap 57 which is preferably provided with a seat, with which the flanges 52 and 54 contact, so that direct metallic contact is had between the cap 57 and the burner elements.

The cap 57 is provided with the chamber 60 therein, into which a liquid, as oil or water is introduced by the pipe 58 and leaves said chamber by the pipe 59, it being evident that the pipe 58 may communicate with the cylinder water jacket 66, if desired.

It will be seen that when the burner elements are assembled, the inner thimble 55 is shorter than the outer cylinder 51 or in other words, its lower edge is positioned slightly above the lower edge of the outer cylinder, but if desired, the burner cylinders may be made the same length, and differently proportioned to carry out my novel method, as explained in connection with Figure 1.

The cap 57 is provided with a passage 61 therethrough into which the fuel is admitted through the pipe 62 to the burner elements assembled as seen in Figure 7.

It will be apparent that there is an outer chamber 63 formed between the cylinder 51 and the wall of the passage in the cylinder, which receives the burner. A thin, annular ignition chamber 64 is formed between the inner thimble 55 and the outer thimble 51. Through the inner cylinder extends a relatively large combustion chamber 65, it being seen from the foregoing that the relatively thin ignition chamber 64 and the central relatively large combustion chamber 65 are in communication at their lower portions and that their upper portions have restricted communication through the small ports 56, whereby pure compressed heated air in carrying out my novel method is initially or primarily admitted to the lighter particles of the fuel segregated from the heavier particles, which latter are in the lower portion of the combustion chamber 65. The process of burning the fuel in the burner construction seen in Figure 7 is the same as that already described with respect to Figure 1, the heat interchanges and the functioning of the combustion and ignition chambers being substantially the same, and it is therefore unnecessary to repeat the operation in detail.

It will be apparent that in all the embodiments of my invention, as in the apparatus seen in Figures 1 and 7, and analogous constructions in which my invention may be carried out, the fuel is admitted into a body of heated compressed air to effect the segregation of the lighter and heavier particles thereof, and said lighter particles rising are primarily or initially ignited, which ignition is effected by the admission of inde-

pendently heated air to said lighter particles. The ignition of the heavier or lower particles of the fuel in the combustion chamber next follows, and the incandescent flame 5 is next projected or expanded into a zone of compressed heated air, there being no explosion in my method but instead a relative gradual slow burning of the fuel, to which I attribute the efficiency I attain.

10 It will be evident that my novel method is not the function of the apparatus, since it is not dependent upon one form of apparatus and can be carried out in various structures, three of which have been heretofore referred to. It will be further understood that in the various types of burners, I have referred to, it is desirable that the thickness of the thin tubular burner elements, the proportions of their flanges or 15 supports and the thickness of the cap member in metallic contact with said flanges or burner elements, as well as the areas of the restricted ports, and the proportions of the central combustion chamber and outer thin 20 ignition chamber have certain proportional relationships, as will be evident to those skilled in the art, but nevertheless I do not desire to be limited to any particular structure or form of burner or apparatus for 25 carrying out my novel steps.

I am the first in the art to employ these novel steps in a burner of any character or in conjunction with a combustion and ignition chamber collocated as described and 30 having communication at their opposite ends or having a restricted port communication at one end and free communication at their other ends and I am also the first to employ said steps in conjunction with chambers of 35 the character aforesaid, whose walls are in metallic contact with a relatively thick cap less susceptible to temperature changes than the burner elements, and acting as a temperature regulating member which keeps the 40 burner elements below destructive temperatures, and my claims are therefore to be interpreted with the scope accorded to inventions of this character.

It will now be apparent that I have devised a new and useful method of burning fuel oil in internal combustion engines which embodies the features of advantage enumerated as desirable in the statement of the invention and the above description, and 45 while I have, in the present instance, shown and described preferred embodiments thereof which will give in practice satisfactory and reliable results, it is to be understood that the same are susceptible of modification in various particulars without departing from the spirit or scope of the invention or sacrificing any of its advantages.

Having thus described my invention what I claim as new and desire to secure by Letters Patent, is:—

1. The method of burning fuel in an internal combustion engine, which consists in introducing the fuel into a chamber in communication with the working space of an engine cylinder and containing compressed air, independently heating a volume of compressed air in free communication with the intake and discharge ends of said chamber, segregating the lighter particles of the fuel, utilizing said independently heated volume of compressed air to ignite said segregated lighter particles of fuel, and permitting the ignited fuel to expand into the working space of the engine cylinder. 70

2. The method of burning fuel in an internal combustion engine, which consists in introducing the fuel into a chamber in communication with the working space of an engine cylinder and containing compressed heated air, independently heating a volume of compressed air in restricted communication with the intake end of said chamber and in free communication with the discharge end of said chamber, segregating the lighter particles of the fuel, utilizing said independently heated volume of air to 75 ignite said segregated lighter particles of the fuel, and permitting the ignited fuel to expand into the working space of the engine cylinder. 80

3. The method of burning fuel in an internal combustion engine, which consists in introducing the fuel into a chamber in communication with the working space of the engine cylinder and containing compressed air, independently heating a volume of compressed air in communication with said chamber only at its intake and discharge ends, segregating the lighter particles of the fuel at the intake end of said chamber, utilizing said independently heated volume of air to ignite said segregated lighter particles of the fuel, and permitting the ignited fuel to expand into a zone of compressed air in the working space of the engine cylinder. 90

4. The method of burning fuel in an internal combustion engine, which consists in introducing fuel into a chamber, communicating with an engine cylinder's working space, and containing heated air, to effect a separation of the lighter and heavier particles of the fuel, igniting the lighter fuel particles by subjecting them to the action of a separately confined volume of heated air surrounding said chamber, in free communication with the intake and discharge ends of said chamber and in free communication with said working space, and permitting the ignited fuel to expand into the working space of the engine cylinder. 100
